UNITED STATES PATENT OFFICE.

JOHN G. C. SIEFKER, OF CHICAGO, ILLINOIS.

ORGAN SOUND-BOARD.

SPECIFICATION forming part of Letters Patent No. 339,224, dated April 6, 1886.

Application filed October 23, 1885. Serial No. 180,760. (No model.)

To all whom it may concern:

Be it known that I, JOHN G. C. SIEFKER, residing at Chicago, in the county of Cook and State of Illinois, and a citizen of the 5 United States, have invented new and useful Improvements in Organ Sounding-Boards, of which the following is a full description.

Heretofore it has been customary to construct the sounding-boards of organs in a parallelogram shape without any attempt to proportion the width and thickness of the same to the gradually-increasing vibration of the reed-tongue in the notes running from the bass to the treble end of the scale.

15 The object of my invention is to improve and strengthen the tones of organs by adapting the sounding-board as nearly as practicable in a gradual taper in width from the bass to the treble end thereof, in order that the vibrations of the reed-tongues may be more nearly in unison than when the sounding-board is of the same width at the bass as the treble end. I also further the above object, if I so desire, by making the sounding-board 20 thickest at the bass end, and gradually decrease it in thickness until it is thinnest at the treble end. Through lack of space in the organ it is impossible to exactly adapt the width of the sounding-board at the bass end 25 so that the same will vibrate in unison or proportion with the deep bass notes. This is particularly so in the smaller instruments. Hence I may not start the taper of the sounding-board at the extreme bass end of the scale, 30 as numbers of the bass notes may require the greatest width of sounding-board obtainable, but in this case will start the taper at a point nearer the treble end of the instrument.

40 The objects above mentioned I attain by the mechanism illustrated in the accompanying drawings, in which—

Figure 1 is a top view of an organ sounding-board as now made; Fig. 2, a rear view of the 45 sounding-board with the rear part cut away in a gradual taper from the extreme bass to the treble end, and also the front part removed in the same way. Fig. 3 is a view of the same with only a portion of the rear of 50 the sounding-board cut away. Fig. 4 is a

view of the same cut away in a curve. Fig. 5 is a longitudinal section of the sounding-board, showing the taper in thickness.

Referring to the drawings, in which similar letters refer to similar parts, A is the sounding-board; B, the cell-board; D, the mutes, and C the sounding-board supports or bearings.

In all of the figures the sounding-board A is broken away, to show the old and my improved method of placing the supports in order to obtain the desired tapering of the sounding-board.

In Fig. 2 the rear support, c, runs in a direct taper from the bass to the treble end, cutting off the portion E of the sounding-board, and can be used when the width of the instrument admits; also, if desired, I may cut away the front part of the sounding-board—that is, the part in front of the cell-board— 70 by placing the support d in the position indicated in the figure.

In Fig. 3 the support e is shown commencing at a point about midway between the bass and treble end, and is used when it is desirable to have the greatest width of sounding-board to vibrate as nearly as may be in unison with a large number of the bass notes.

Fig. 4 simply shows the use of a curved support, g, which may run from any point at 80 or near the bass end to the treble end of the scale, as the width of the instrument admits.

If desired, in every instance the sounding-board may extend over the supports, so as to obtain a parallelogram shape as a matter of 85 convenience in the construction of the organ, provided the same be attached or fastened to the supports, which, in effect, gives the taper to the same.

What I claim as new, and desire to secure 90 by Letters Patent, is—

1. In an organ, the sounding-board made narrower at the treble than the bass end thereof, substantially as described, and for the purposes set forth.

2. In an organ, the sounding-board wherein the vibrating board between the reed-tongues and the supports shall be widest at the bass, and taper to the treble end thereof, where it shall be narrowest, substantially as described. 100

3. In an organ, the sounding-board thickest at the bass end, and gradually decreasing in thickness to the treble end thereof, substantially as described.
- 5 4. In an organ, the sounding-board so constructed as to be both thicker and wider at the bass than the treble end, and gradually de-

creasing in thickness and width from the former to the latter, substantially as described, and for the purpose set forth.

JOHN G. C. SIEFKER.
